His Attorney.

UNITED STATES PATENT OFFICE.

WILHELM KÖCHLING, OF BERLIN, GERMANY, ASSIGNOR TO GENERAL ELECTRIC COMPANY, A CORPORATION OF NEW YORK.

CORRUGATED VESSEL.

1,206,717.

Specification of Letters Patent. Patented Nov. 28, 1916.

Application filed June 5, 1914. Serial No. 843,157.

To all whom it may concern:

Be it known that I, WILHELM KÖCHLING, a subject of the King of Prussia, residing at Berlin, Germany, have invented certain new and useful Improvements in Corrugated Vessels, of which the following is a specification.

My invention relates to corrugated walls and vessels, such, for example, as transformer tanks, and the object of my invention is to provide a corrugated wall with a portion better adapted to be readily and firmly attached to an adjoining wall or other body than is a simple corrugated edge. It is fairly obvious, and has long been understood, that a joint made to the edge or side or both of a corrugated wall is unsatisfactory and difficult to make, and various expedients have already been resorted to to secure a better joint between a corrugated wall and an adjacent body. In carrying out my invention, I propose to modify the end of the corrugated wall in a novel manner, so that it may be fairly readily welded or otherwise attached to another body, as a band or another portion of the vessel; preferably I carry the modification so far as to produce an attaching edge which is more nearly straight than the unaltered corrugated edge of the sheet.

An application of my invention will be understood by reference to the accompanying drawings; this application is described in detail below. Structures embodying my invention have substantial advantages over those structures produced prior to my invention; among these may be enumerated the following: The seam is ready of access but is within the outlines of the vessel and protected from blows. The slanting of the ends of the corrugations renders the cover, or any other part of the structures adjacent the ends of the corrugations, of ready access. Adjacent the attaching edge, parts of the corrugated metal extend inwardly, thereby affording additional opportunity for the exchange of heat between the walls of the vessel and its contents.

In the accompanying drawing which forms a part of this specification, Figure 1 is a perspective view of an end portion of a simple corrugated wall; Figs. 2 and 3 illustrate such a corrugated wall as modified in applying my invention; and Fig. 4 is a

sectional view showing the wall of Fig. 3 attached to a band.

My invention may be embodied in corrugated walls or vessels made of either cast or sheet metal. It will more readily be understood perhaps from a description of the steps gone through in modifying a corrugated sheet metal wall.

In Fig. 1 is shown a portion of an end of a sheet metal corrugated wall; for the purposes of this specification I shall call the portion 1, 2, 3, 4 a single corrugation. Taking such a sheet I bend the end portion of each corrugation to be treated at an angle to the wall, as illustrated in Fig. 2; preferably, this portion is so selected that the terminal edges of the corrugations make an angle of approximately 45 degrees with the extent of the corrugation. Thus it will be seen that the point 3 of Fig. 1 has been bent inwardly to the point 3' of Fig. 2 and that the terminal edges 1-5 and 2-5 of this corrugation, since the distance 3-5 has been chosen approximately equal to the depth of the corrugation 1, 2, 3, make angles of approximately 45 degrees with the extent of the corrugation. After each of the corrugations to be treated has been bent in this way, I prefer to proceed to join together a portion of each of the faces 1, 3', 5 and 2, 3', 5, to form a ridge 3', 5, 6 projecting away from the bent portions, producing a shape something like that illustrated in Fig. 3. From this figure it will be seen that the portion 3', 5, 6 of each of the faces 1, 3', 5 and 2, 3', 5 have been made to substantially engage each other. These surfaces 3', 5, 6 may be attached together, for example by welding them along their meeting edges 3, 6 and 5, 6, if desired. Now, the extent of the engaging surfaces 3', 5, 6 relative to the surfaces 1, 3', 5 and 2, 3', 5 is more or less immaterial. It is quite possible to weld or otherwise attach a band to the edge of which 1, 3', 2, (Fig. 2) is a part, that is, to the free ends of the bent portions of the corrugations, and such a structure possesses some advantages over the prior practice, but first performing the further step of engaging the surfaces 3', 5, 6 produces a better structure. Preferably then the structure of Fig. 3 is welded or otherwise attached along the free ends of the bent portions of the corrugations, 1, 6, 2, etc., to a band, an adjacent

90

100

105

wall or any other body offering a coöperative surface. In Fig. 4 is shown such a structure welded to a band 7. It will be noticed that the edge 3', 6 may also be attached 5 to the band 7 in this case, the ridge 3', 5, 6 providing an additional point of support for the band 7.

When producing a structure embodying my invention from sheet metal, the steps 10 have outlined may be followed, though the process itself forms no part of my invention which I propose to claim here. If the wall is to be of cast metal the wall may be cast into the desired shape at first instance. 15 Especially in a cast wall it may be desirable to leave off the portion 3', 5, 6 entirely, although the attaching edge is given the form 1, 6, 2 of Fig. 3. It will be understood that in the case of cast structures as well as in 20 sheet metal structures, the angles 1, 5, 4 and 1, 6, 2 and 6, 5, 3' (or 6, 5, 4) may be either greater or less than those illustrated in the drawing and that more or less of the total number of corrugations may be treated:

25 While I have described the principle of my invention and the best mode I have contemplated for applying this principle, other modifications will occur to those skilled in this art and I aim in the appended claims 30 to cover all modifications which do not involve a departure from the spirit and scope of my invention.

What I claim as new and desire to secure by Letters Patent of the United States, is,— 35 1. A corrugated wall, the ends of some of the corrugations being bent at an angle to the wall and located within such corrugations, and a body attached to the free ends of such bent portions.

40 2. A corrugated wall, the ends of some of the corrugations being bent at an angle to the wall and located within such corruga-

tions a portion of the adjacent faces of each bent portion engaging with each other to form a ridge projecting away from those 45 bent portions.

3. A corrugated wall, the ends of some of the corrugations being bent at an angle to the wall and located within such corrugations a portion of the adjacent faces of each 50 bent portion engaging with each other to form a ridge projecting away from those bent portions, and a body attached to the free ends of such bent portions.

4. A corrugated wall, some of the corrugations terminating at an angle to their extent and each of such corrugations being provided with a portion located within such corrugations adjacent the ends thereof and 55 inclosing the space within such corruga- 60 tions.

5. A corrugated wall, some of the corrugations terminating at an angle to their extent and each of such corrugations being 65 provided with a portion located within such corrugations adjacent the ends thereof and inclosing the space within such corrugations, and a body attached to the free edges of such inclosing portions.

6. A corrugated wall, some of the corrugations terminating at an angle to their extent and each of such corrugations being provided with a portion having generally 70 triangular outlines joined at two edges to the terminal edges of the corrugation and forming a cap for the end of such corruga- 75 tion.

In witness whereof I have hereunto set my hand this 19th day of May, 1914.

WILHELM KÖCHLING.
